J. HALL.
MACHINE FOR MAKING CORDAGE.

No. 65,565.

Patented June 11, 1867.

Inventor:

James Hall

United States Patent Office.

JAMES HALL, OF MONROE TOWNSHIP, NEW YORK.

Letters Patent No. 65,565, dated June 11, 1867.

IMPROVEMENT IN MACHINE FOR MAKING CORDAGE.

The Schedule referred to in these Letters Patent and making part of the same.

TO ALL WHOM IT MAY CONCERN:

Be it known that I, JAMES HALL, of the township of Monroe, in the county of Orange, and State of New York, have invented certain new and useful Improvements in Machinery for Making Fish-Lines, Netting, and other Cordage; and I hereby declare the following to be a full, clear, and exact description thereof, reference being had to the accompanying drawings, which are lettered to correspond with and form a part of the specification.

To enable those skilled in the art of cord or rope-making to construct and use my invention, I will describe it as follows:

A is a stationary wooden framework, provided with a drum, D, which is operated by the main belt R by any suitable power. The drum D operates the horizontal shafts K and N and spindles 1 2 3 by means of the belts P P P' and cords m m m. T is a reciprocating truck upon the ways W W, and is operated by the endless rope or belt which passes over the concave pulley N' on shaft N, and through the pulley-block O. This endless belt or rope is fastened to the bottom of the truck T, hence must carry it backwards and forwards upon the ways when operated by the shaft N. This truck is furnished with two rollers E E', placed one upon the other, and operated by means of the belt B passing over the top roller E and around the axle α of the truck T. The rollers E and E' regulate the tension of the cords c c c as they are fed from the spools to the spindles 1 2 3 by the backward movement of the truck produced by the cross-belt P' at the back end of the frame A.

Hence all the working parts of the above-described apparatus are simultaneous in their movements, produced by the revolutions of the drum D, by which means a more uniform and better article of cordage is produced. By the above-described arrangement I am enabled to attach any number of threads or partially twisted small cords c c c to the spindle-hook or hook 1 2 3; or the threads c c c from the different spools may be secured to a single spindle-hook, 2, thereby twisted into a rope or large cord.

Claim.

Therefore, what I claim as new and useful, and what I wish to secure by Letters Patent of the United States, is—

The arrangement of the spindles 1 2 3, drum D, truck T, ways W W, and rollers E E', with the endless rope or belt B, all operating together in the manner and for the purpose set forth.

In testimony whereof I hereunto subscribe my name in the presence of two witnesses.

JAMES HALL.
